3 Claims. (Cl. 200—147)

This invention relates to circuit interrupting devices and more particularly to means for reducing the amount of ionized gas discharge above the arc chute of a circuit breaker structure.

In the construction and operation of circuit breaker structures, it is frequently necessary to provide means for extinguishing quickly the arc which is drawn between separable arcing contacts. This arc is usually blown by blowout means, such as a magnetic blowout coil or an air blast, into an arc chute which is arranged to quench the arc by lengthening it, cooling it, or a combination of both.

Arc chutes having spaced insulating plates to lengthen the arc or squeeze the arc into narrow slots have been used to rapidly increase the arc voltage, decrease the arc current and greatly improve the power factor, thereby facilitating interruption of the arc at a natural or forced current zero. However, it has been found in many cases that the arc voltage developed by the arc chute was not the most favorable for interrupting the power circuit.

The arc chute for an electromagnetic type of circuit breaker is designed to perform two functions, namely, to interrupt a power circuit and to enclose the arc products. As a circuit interrupting device the arc chute of the magnetic breaker must be capable of controlling the arc voltage, the arc current, the arc energy, the rate of rise of recovery voltage and the phase relationship between arc current and line voltage at the instant of interruption. As an enclosing structure for cooling and deionizing the arc products, the arc chute of the magnetic breaker must protect all the surrounding operating parts from the effects of the arc or its arc products. All of the gases exhausted from the arc chute must be rendered harmless before being exposed to any of the surrounding circuit breaker structure or allied equipment. In many cases, however, the gases exhausted from the arc chute remained ionized and caused a visible discharge, such as flame emission, at the exhaust end of the arc chute structure.

Therefore, in accordance with the invention claimed a new and improved arc interrupting device is provided which cools the gases exhausted from the interrupting device within the arc chute enclosure before final discharge of the gases to atmosphere, thereby eliminating or substantially reducing ionized gas discharge or flame emission from above the arc chute of the interrupting device. The arc chute comprises a plurality of spaced insulating plates arranged to extend longitudinally of the axis of the arc chute at the arc receiving end thereof, a pair of spaced arc runners, one of said arc runners being arranged adjacent each of the contacts for providing a conductive path for the terminals of the arc from the contacts into the arc chute, and a plurality of spaced cooling elements arranged above the arc runners and spaced from the insulating plates at the exhaust end of the arc chute for deionizing the arc products.

It is, therefore, one object of the present invention to provide a new and improved arc interrupting device in

2

which reduction of ionization and visible discharge at the exhaust end of the arc chute is accomplished by cooling the arc products and gases within the arc chute enclosure before discharge to atmosphere.

Another object of this invention is to provide a new and improved arc interrupting device in which arc discharge cooling means function to cool the arc products and gases without offering a pneumatic impedance to their flow.

10 A further object of this invention is to provide a new and improved arc interrupting device in which cooling elements are arranged in a predetermined manner above the arc runners in the exhaust end of an arc chute structure to reduce ionization and visible discharge therefrom.

15 A still further object of this invention is to provide a new and improved arc interrupting device in which arc discharge cooling means arranged in a chimney vent above the arc runners at the exhaust end of the arc chute are staggered and insulatingly separated from each other.

20 A still further object of this invention is to provide a new and improved arc interrupting device in which arc discharge cooling means are arranged downstream of the arc runners and across the exhaust end of the arc chute structure.

25 Objects and advantages other than those above set forth will be apparent from the following description when read in connection with the accompanying drawings, in which:

Fig. 1 is a view in cross section of a magnetic blowout type circuit breaker employing the present invention;

Fig. 2 is a partial, cross sectional view of a modification of the cooling element arrangement illustrated in Fig. 1;

30 Fig. 3 is an end view of the structure illustrated in Fig. 2 with the arc chute end plate removed;

Fig. 4 is a plan view of the structure illustrated in Fig. 2;

35 Fig. 5 is an enlarged perspective view of the cooling elements arranged above the arc runners shown in Fig. 1; and

Fig. 6 is a partial cross sectional view of a modification of the arc runner cooling element arrangement illustrated in Figs. 2, 3 and 4.

40 Referring more particularly to the drawings by characters of reference, Fig. 1 illustrates a magnetic blowout type of circuit breaker including as elements thereof a pair of terminal studs 6 and 7 for connecting the circuit breaker to line conductors (not shown). Although in general, circuit breakers of the type considered in Fig. 1 are provided with a plurality of similar pole structures, one for each phase of a polyphase electric circuit, only one such pole structure is shown in the drawings and the circuit breaker will be described in detail as if it was of the single pole type.

45 The circuit interrupter or breaker in Fig. 1 comprises essentially means for opening the circuit to form the interrupting arc and an arc extinguishing structure. Specifically the circuit opening means comprises a fixed current carrying contact 8, a tertiary contact 9, a fixed arcing contact 10, and a movable arcing contact 11. Arcing contact 11 is mounted on a contact arm 12 which is pivotally mounted at 13 on an extension 14 of the circuit breaker stud 6 and is operated by means of a reciprocally movable rod 15. The operating rod 15 is suitably connected to an actuating mechanism (not shown) for operating the movable contact between closed and open circuit positions. Fig. 1 illustrates the movable contact 11 in closed position. The arcing contacts are electrically connected to the lower ends of terminal studs 6 and 7. Accordingly, when the breaker is connected in series in a power circuit and the arcing contacts are separated, an arc

50 55 60 65 70

may be initiated across the gap formed between the contacts.

For interrupting this power arc, an arc extinguishing structure, such as an arc chute 16, may be mounted so as to receive the power arc which is under the influence of the magnetic blowout means. The arc chute preferably is disposed directly about and above the arcing contacts, as shown, when the blowout means act upward, but may be mounted in any other suitable location when the blowout means act in other directions. The switch or arcing contacts and the magnetic blowout structure can assume any preferred form so that a brief description thereof will be sufficient. The magnetic blowout means may comprise a core 17, poles 18 and a coil 19 which is electrically connected to the terminal stud 7 and to a metallic arc runner 20 so that the arc current (as the arc travels along the runner) flows through the blowout coil in a manner well known in the art.

Normally the current is carried in the closed circuit position of the breaker by the spring biased contact 8. As the movable arcing contact 11 is actuated to open circuit position, current is shunted from fixed contact 8 first to fixed contact 9 and afterwards to fixed arcing contact 10. As the arc is drawn by the movable arcing contact 11, the arc terminal of arcing contact 10 is transferred to arc runner 20, which is usually an extension arm of the fixed arcing contact 10. As the movable arcing contact 11 approaches or reaches its full opening stroke the arc terminal transfers from the movable arcing contact 11 to an arc runner 21 which directs the arc in the arc chute 16. The arcing contact 10 and the arc runner 20 are electrically connected in series with the blowout coil 19 and stud 7. Accordingly, the blowout coil is already energized at the inception of the arc to influence the arc in a well known manner, i.e. to drive it in the arc chute 16 in an expanding loop. It will be apparent to one skilled in the art that the blowout field can be utilized in the most efficient manner by disposing the iron poles 18 so as to cooperate with the blowout coil in the conventional manner outside of the arc chute.

Arc chute 16 is provided with a plurality of slotted spaced insulating barrier plates 22 arranged to extend longitudinally of the axis of the arc chute. If desired these barrier plates may be arranged in groups with each group comprising a plurality of types of barrier plates having different geometrical configurations. Slots 23 of barrier plates 22 are aligned at their upstream ends adjacent the zone of arc initiation to form an arc passage. As well known in the art the slots may be arranged in staggered relation at their downstream ends. This out of registry or staggered relationship of the slots causes the formation of a zigzag shaped arc path. Barrier plates 22 may be provided in some applications of this invention with a plurality of apertures or perforations which may be arranged to extend from the downstream ends of slots 23 toward the exhaust end of the arc chute.

Chimney vents 24 and 25 are arranged at each end or side of the stack of barrier plates 22 above arc runners 20 and 21. These vents direct the arc products and gases created by the arc terminals moving along the arc runners out of the arc chute to atmosphere. The extent of the ionization of the gas and the volume of the arc products produced by the action of the arc on the arc runners varies directly with the amount of current being interrupted and the voltage characteristics of the interrupter. It is recognized that the arc products may interfere with the action of the barrier plate stack. Consequently chimney vents 24 and 25 are separated from the barrier plate stack and discharge the gases and arc products from the arc runners directly to atmosphere without going through the barrier plate stack. As noted from the drawings the arc runners direct the terminals of the arc into the chimney vents.

The chimney vents while accomplishing their purpose of separating the arc products of the arc runners from the

barrier plate stack produce a concentration of these products downstream of the arc runners. It has been found that these arc products from the chimney vents are the chief cause of dielectric difficulties outside of the confines of the breaker. Since the arc products from the arc runners are discharged from a live terminal, this terminal is in effect extended to the full distance the products travel while in an ionized condition. If no insulation is present to isolate the terminals, the terminals will discharge to ground. For high current interruption this means that the circuit breaker enclosure must be well insulated or that the distances between the ionized gas discharge from the chimney vents and any grounded structure be sufficient to assure that ionized arc products 10 do not touch grounded metal.

It has been noted that the arc within the breaker structure will not travel beyond the height of the barrier plate stack. Therefore, it is possible pneumatically to place metallic cooling elements in close proximity to and downstream of the tops of the arc runners without the arc terminals jumping from one cooling element to another. Even though the potential of the arc runner is impressed to the distance the gases remain ionized within the chimney vent, nevertheless beyond the arc runner the dielectric strength of the air column is increased proportionally to the condition of the gas or air within the breaker structure and later to the mixture of gas and air between the arc chute structure or chimney vents and the grounded enclosure. The current interrupting limitation of the 20 breaker structure, therefore, is that amount of current required to cause ionized gases to extend from the chimney vents to the grounded circuit breaker enclosure and cause an arc discharge to ground to occur.

In order to increase the interrupting ability of air type 30 circuit breaker structures the arc chutes in accordance with the invention claimed are provided with a plurality of cooling elements, which, for example, may be metallic or nonmetallic tubular members 30, arranged above the arc runners 20 and 21 and spaced from the barrier plates 22 at the exhaust end of the arc chute. If so desired, these cooling elements may be solid or hollow tubular members of a material having a high specific heat value. When chimney vents are employed above the arc runners, as shown in Figs. 1 and 2 of the drawings, 40 the cooling elements 30 are arranged to extend from and are supported by the insulating members 34 forming the sides of the chimney vents and are arranged transversely to the longitudinal axis of the arc chute. Because of the rectangular shape of the usual chimney vent the longitudinal axis of the cooling elements extends substantially parallel with the short axis of the vent, however, it is intended to be within the scope of this invention to provide cooling elements of any suitable cross sectional form arranged to extend in any desirable direction 45 within the chimney structure. In most applications the cooling surfaces of the elements are so arranged that they offer the least amount of pneumatic impedance to the flow of gases and arc products through the chimney vents. For this reason and for the further reason that 50 the voltage of the arc runner is impressed only as far as ionization travels through the chimney vents, separate cooling elements 30 are positioned in rows in spaced staggered relationship to one another, such that, while ostensibly presenting a solid front of cooling elements to the flow of gases, sufficient space remains between the cooling elements to allow nearly unrestricted flow of gases and arc products through the chimney vents. At the same time a ladder-like electrical path beyond the 55 point of deionization of the arc products is precluded.

As noted from Figs. 1 and 2 of the drawings, a plurality of spaced tubular cooling elements such as, for example, metallic, nonmetallic or insulating tubes 31 may be arranged within the exhaust passage 32 substantially 60 completely across the exhaust end of the arc chute 16 above or downstream of the barrier plates 22. Tubes 70

75

31 are arranged in isolated groups to extend transversely to the longitudinal axis of the arc chute and to the direction of movement of the arc, arc products and gases through the arc chute structure. Each group may be separated or compartmented from the adjacent groups by insulating material 33. The size and number of compartments used in a particular arc chute structure is determined by the voltage gradient across the arc chute. Each group of tubes is exposed to and reacts on only a portion of the voltage across the arcing contacts or arc runners.

Compartmentization of the arc chute structure assures that each group of tubes or cooling elements functions to its fullest capacity by cooling only a certain portion of the generated gas and arc products. The number of tubes used and their geometrical arrangement within the arc chute enclosure is determined by the amount of cooling required and the particular position and amount of discharge volume of arc products and gases from the barrier plate stack. Tubes 31 are staggered in such a manner that the space between them provides full discharge of the arc products and gases from the arc chute structure at the same time being so arranged that the arc products and gases discharged from the barrier plate stack must pass adjacent to the cooling elements 31 before being discharged to atmosphere. In this manner cooling is accomplished without restriction to the normal flow of gases or arc products.

The group of cooling elements arranged adjacent each end of the arc chute barrier plates comprises a greater number of cooling elements which extend farther downstream from the arcing contacts than do the elements of the groups arranged intermediate the ends of the arc chute structure. This arrangement provides a larger number of cooling elements immediately above the zones of the greatest arc product and gas discharge production from the barrier plate stack, namely, above the areas adjacent the ends of the arc chute structure and near the zones of the arc runners than do the groups intermediate the ends of the arc chute structure.

If so desired the respective groups of cooling elements 31 may be arranged in removable or detachable compartments which can be temporarily arranged in a given position in the arc chute structure and later moved to another more effective position. The tubes of each compartment are arranged in a plurality of rows wherein each cooling element of each row is arranged in staggered relationship to the elements of adjacent rows. At least some of the cooling elements in at least one of the groups may be composed of insulating material. In the removable compartment structures the walls of the compartments are made of insulating material of the type capable of withstanding the heat of the arc products and gases.

The cooling elements 30 and 31 are arranged as after coolers in the exhaust end of the arc chute structure and are spaced a predetermined distance downstream from the arc runners and the barrier plates. These elements or tubes function to cool the arc products or gases without offering a pneumatic impedance to their flow. In other words, the performance of the barrier plate stack is not affected by pneumatic blocking and the full arc interrupting ability of the barrier plate stack is developed.

Fig. 2 illustrates an enlarged partial cross sectional view of a modification of the arc chute structure shown in Fig. 1 wherein the insulating tubes 31 are arranged in similar groups across substantially the full length of the exhaust end of the arc chute structure. Fig. 3 is an end view of Fig. 2 with the arc chute end plates removed wherein the particularly geometrical arrangement of the cooling elements 30 is evident. Fig. 4 illustrates a plan view of Fig. 2 showing the manner in which the cooling elements or tubes extend across the exhaust ends of the barrier plates 22.

Fig. 5 is a perspective view of the cooling elements 30 shown in Fig. 1 but illustrates one way of fastening the

5 tubes to a wall of the chimney structure. As noted from Fig. 5 the chimney vent and cooling elements may be separately assembled and detachably connected to the circuit breaker structure.

10 Fig. 6 illustrates a further modification of the cooling element chimney vent arrangement shown in Figs. 1 to 5, inclusive, wherein the cooling elements 30 extend part way into and are firmly held by the side walls of the chimney structure.

15 Although but a few embodiments of the present invention have been illustrated and described, it will be apparent to those skilled in the art that various changes and modifications may be made therein without departing from the spirit of the invention or from the scope of the appended claims.

What is claimed is:

20 1. An electric circuit interrupter comprising a pair of relatively movable contacts, means for drawing an arc between said contacts, an arc chute for receiving the arc at one end thereof and exhausting the arc products at the other end, said arc chute comprising a plurality of spaced insulating plates arranged to extend longitudinally of the axis of said chute at the arc receiving end thereof, a chimney vent arranged adjacent said plates outside of said chute, an arc runner arranged adjacent one of said contacts for providing a conductive path for the terminal of the arc from said one of said contacts into said vent, a plurality of spaced tubular cooling elements arranged to extend transversely to the longitudinal axis of said chute above said runner and within said vent, and a plurality of groups of spaced tubular cooling elements arranged adjacent said plates at the exhaust end of said chute, said groups of said cooling elements being arranged transversely to said plurality of spaced tubular cooling elements, said cooling elements in said vent and adjacent said plates cooling and deionizing the gases and arc products occurring during circuit interruption.

25 2. An electric circuit interrupter comprising a pair of relatively movable contacts, means for drawing an arc between said contacts, an arc chute for receiving the arc at one end thereof and exhausting the arc products at the other end, said arc chute comprising a plurality of spaced insulating plates arranged to extend longitudinally of the axis of said chute at the arc receiving end thereof, a pair of chimney vents arranged adjacent said plates outside of said chute, a pair of spaced arc runners, one of said runners being arranged adjacent each of said contacts for providing a conductive path for the terminals of the arc from said contacts into each of said vents, a plurality of spaced tubular cooling elements arranged to extend transversely to the longitudinal axis of said chute above said runners and within said vents, and a plurality of groups of spaced tubular cooling elements arranged adjacent said plates at the exhaust end of said chute, said cooling elements of said groups being arranged substantially ninety degrees out of phase with said plurality of spaced tubular cooling elements, said cooling elements in said vents and adjacent said plates cooling and deionizing the gases and arc products occurring during circuit interruption.

30 3. An electric circuit interrupter comprising a pair of relatively movable contacts, means for drawing an arc between said contacts, an arc chute for receiving the arc at one end thereof and exhausting the arc products at the other end, said arc chute comprising a plurality of spaced insulating plates arranged to extend longitudinally of the axis of said chute at the arc receiving end thereof, a pair of chimney vents arranged adjacent said plates outside of said chute, a pair of spaced arc runners, one of said runners being arranged adjacent each of said contacts for providing a conductive path for the terminals of the arc from said contacts into each of said vents, a plurality of spaced tubular cooling elements arranged to extend transversely to the longitudinal axis of said chute above said runners and within said vents, a plurality of

groups of spaced metallic tubular cooling elements arranged adjacent said plates at the exhaust end of said chute, said cooling elements of said groups being arranged substantially ninety degrees out of phase with said plurality of spaced tubular cooling elements, and insulating means arranged between each of said groups of said elements for isolating said groups of elements from each other, said groups of elements adjacent each side portion of said chute comprising a greater number of said elements than said groups intermediate the side portions of 10 said chute.
